UNITED STATES PATENT OFFICE.

CHARLES C. GARNER, OF COVINGTON, KENTUCKY.

INK-FEEDING ROLLER.

Application filed May 22, 1923. Serial No. 640,762.

To all whom it may concern:

Be it known that I, CHARLES C. GARNER, a citizen of the United States, residing at Covington, in the county of Kenton and 5 State of Kentucky, have invented certain new and useful Improvements in Ink-Feeding Rollers, of which the following is a specification.

My invention relates to improvements in 10 ink feeding rollers for printing presses of the type which are particularly well adapted for double width newspaper presses, while not necessarily restricted to this use.

In operating these double width news- 15 paper presses different sizes of paper are used at different times, which necessitates the use of a different ink feeding roller for every size of paper to be used.

The object of my invention is to construct 20 a roller which may be readily adapted for use with any of the different sizes of paper now in use on these printing presses.

Another object of the invention is the provision with a device of this character of a 25 novel securing means for the sleeves or bushings.

Another object of the invention is to provide a device of the character which is characterized by simplicity of operation and 30 construction and which will be strong and durable.

Other objects and advantages of the invention will be apparent during the course 35 of the following description.

In the accompanying drawings which form a part of this specification, and in which like numerals are employed to designate like parts throughout the same,

Figure 1 is a side elevation of my im- 40 proved roller, parts being in section and other parts being broken away,

Figure 2 is a top plan view of my device as it is when used with a reduced size of 45 paper,

Figure 3 is an end elevation of Figure 1, and,

Figure 4 is a transverse section taken on line 4—4 of Figure 1.

In the drawings, wherein for the purpose 50 of illustration is shown a preferred embodiment of my invention, the numeral 10 designates the roller stock which is of the same width as the widest size of paper used on the press and which has reduced extensions 55 11 formed on each of its ends. These re-

duced extensions carry journals 12 which fit in the usual bearings of the press.

The stock 10 is provided with a longitudinal keyway 13, which extends throughout its entire length. Sleeve sections 14 and 60 15 are slidably mounted on the stock 10 and have longitudinal keys 16 which are of the same size and shape as the keyway 13 and are adapted to snugly fit therein. The sleeve section 14 is arranged in the center 65 of the stock 10 and is of a size to correspond with the smallest size of paper used on these types of presses, this size being considerably larger than the size of the smaller end sleeve sections 15. These sleeve sections are cov- 70 ered with a layer composition 17 of the kind usually used on these rollers and this layer of composition extends to the ends of the smaller end sections and has its outer edge bevelled as at 18. The composition layer 75 is cut at the points of the sleeve sections and these sections are therefore separate and distinct.

Clamping blocks 19 are arranged one at 80 each end of the stock 10 and to one side of the keyway 13. Each of these blocks has a longitudinally extending slot 20 for the reception of a bolt or screw 21. This block is arranged with one end engaging the end of the stock 10 and its lower face resting on the 85 reduced extension 11. The screw 21 is screwed into the end of the stock 10 and the sleeve sections will be securely held in place. These blocks are of a height so as to reach from the reduced extensions to the top 90 surface of the sleeve sections and are the same width as the keyway.

In operation, when only the center sleeve 95 14 is being used, the clamping blocks 19 are arranged in the keyway 13 and to each side of the sleeve. The screws or bolts 21 are screwed into the openings 22 and the sleeve is clamped in place. If one of the end sections is used together with the center section, then one of the blocks is ar- 100 ranged on the reduced extension 11 and the other is arranged in the keyway. As the slots 20 are considerably wider than the screws 21, the blocks are capable of adjustment besides that afforded by the series of 105 openings 22. These slots also allow adjustment without removing the screws from the openings.

It will therefore be seen that I have pro- 110 vided a very simple and efficient device

which will eliminate the six extra rollers used on this type of printing press. This construction is such that a part of the roller is always in use and when a half size roller is wanted, the two small end rollers may be used in place of the large center one, and thus it is possible to keep the roller a uniform size.

It is to be understood that the form of 10 my invention herewith shown and described is to be taken as a preferred example of the same, and that various changes in the shape, size, and arrangement of parts may be resorted to without departing from the 15 spirit of my invention, or the scope of the subjoined claims.

Having thus described my invention, I claim:

1. In a device of the character described, 20 a roller stock having a longitudinal keyway extending throughout its length, sleeve sections adapted to be removably mounted upon the stock and having longitudinal keys to engage the keyway in the stock, and 25 clamping blocks of the same width as the keyway, said clamping blocks being normally arranged on the end of the roller stock but capable of being arranged within the keyway when any of the sleeve sections are removed.
2. In an ink feeding roller, a roller stock having a longitudinal keyway extending throughout its length, journals carried by the roller stock, sleeve sections removably

mounted on the roller stock and having keys 35 to engage the keyway in the roller stock, said sleeve sections having a layer of composition on their surfaces, locking blocks to lock the sleeves on the stock, said locking blocks being of the same width as the keyway in the roller stock and being adapted 40 to be located either at the ends of the roller stock or within the keyway, and means carried by the locking blocks for independently adjusting said blocks. 45

3. In a device of the character described, a roller stock having a longitudinal keyway extending throughout its entire length, reduced extensions carried by the roller stock at each of its ends, journals carried 50 by the reduced extensions, sleeve sections removably mounted on the roller stock and having longitudinal keys to engage the keyway in the roller stock, and locking blocks adapted to rest on the reduced extensions and 55 to be clamped to the end of the roller stock so as to retain the sleeve sections on the stock, said locking blocks being of the same width as the keyway and capable of being located within the keyway when any of 60 the sleeve sections are removed, said blocks also having slots to receive clamping screws, the slots being of a size to allow the blocks to be shifted for adjustment, with the screws 65 in position.

In testimony whereof I affix my signature.

CHARLES C. GARNER.
